UNITED STATES PATENT OFFICE.

HENRY H. MORETON, OF STONY POINT, NEW YORK.

GAS-BURNER.

1,180,175.

Specification of Letters Patent. Patented Apr. 18, 1916.

Application filed May 23, 1913. Serial No. 769,520.

To all whom it may concern:

Be it known that I, HENRY H. MORETON, a citizen of the United States, residing at Stony Point, in the county of Rockland and 5 State of New York, have invented new and useful Improvements in Gas-Burners, of which the following is a specification.

This invention relates to an improved gas burner, being particularly designed for use 10 in the burning of Bunsen gases, *i. e.*, those gases in which the combustible ingredients are intermixed with the necessary volume of atmospheric air or oxygen to support the combustion thereof.

15 The invention has for its object the provision of improved means by which the illuminating efficiency of a burner of this type may be materially increased.

A further object is to provide a burner 20 of this character which may be readily placed in position or removed as desired and which is composed of so few parts that it cannot become deranged or get out of order.

A further object is to provide improved 25 means whereby the burner may be regulated.

The invention will be hereinafter fully set forth and particularly pointed out in the claims.

In the accompanying drawings:—Figure 30 1 is a longitudinal sectional view illustrating my improved burner. Fig. 2 is a top plan view of the regulating cap. Fig. 3 is an enlarged transverse sectional view thereof.

35 Referring to the drawings, 10 designates a gas pipe leading from any suitable gas supply into the burner tube 11, the latter being provided with the usual gauze 12 ordinarily employed where an incandescent 40 mantle, as 13, is utilized for illumination. The burner tube is provided with a flat plate or tray 14 provided with upstanding arms 15, serving as a support for a chimney 16. It will be noted that when the chimney is 45 in place no air can enter the same from the bottom.

I have found, in dealing with Bunsen gases, that if the outlet for the products of combustion in the chimney 16, is restricted 50 the illuminating power of the gas is greatly increased, and the character of the illumination will vary as the size of the outlet of said chimney is varied. I accordingly provide a regulator comprising a cap 20 having 55 an annular flange 21 adapted to fit over the

upper end of the chimney 16, said cap being provided with openings 22 adapted to register with openings 23 in a rotating slide 24 secured to said cap. If desired the openings may be covered with gauze. By rotating 60 the slide 24 the outlet from the chimney 16 is increased or diminished, as may be, and the illumination correspondingly varied. For instance I have found that by igniting the gas as it is discharged from the burner 65 tube, and with the upper end of the chimney open, and then placing my regulator attachment over the upper end of said chimney, the illuminating power of the gas is increased approximately twenty-five per cent. 70

In practice the regulator 20 is removed from the chimney in order to ignite the gas issuing from the burner. And after igniting said gas, the cap is immediately replaced. The slide 24 is then adjusted to 75 secure the desired illumination. Should the quantity of oxygen carried by the gas become diminished for any reason, the cap may be removed to permit atmospheric air to reach the burner. 80

Having thus explained the nature of my invention, and described an operative manner of constructing and using the same, although without attempting to set forth all 85 of the forms in which it may be made, or all of the modes of its use, what I claim is:—

1. A gas burner of the character described comprising a burner tube provided with an imperforate chimney-supporting plate, a chimney resting upon said plate and inclosing said burner tube, and a cap provided with a flat under surface resting upon and in close contact with the upper edge of said chimney, said cap being provided with means for regulating the outlet of the products of combustion. 90

2. A gas burner of the character described comprising a burner tube, a chimney surrounding said tube closed at its bottom, and a cap provided with a flat under surface 100 resting upon and in close contact with the upper edge of said chimney, said cap being provided with means for regulating the outlet of the products of combustion.

3. A gas burner of the character described comprising a burner tube, a chimney surrounding said tube closed at its bottom, and a cap provided with a flat under surface resting upon and in close contact with the upper edge of said chimney, said cap being 105 110

provided with means for regulating the outlet of the products of combustion, said cap having an annular flange fitted around the periphery of said chimney.

- 5 4. A gas burner of the character described comprising a burner tube, a chimney surrounding said tube closed at its lower end, a cap provided with a flat under surface resting upon and in close contact with the upper 10 edge of said chimney, said cap being pro-

vided with the outlet openings, and a rotatable slide controlling said openings.

In testimony whereof I have hereunto set my hand in presence of two subscribing witnesses.

HENRY H. MORETON.
